US00D772206S

(12) **United States Design Patent** (10) **Patent No.:** **US D772,206 S**
(45) **Date of Patent:** **** Nov. 22, 2016**

(54) **COMMUNICATIONS POLE WITH
ANTENNA-LUMINARY ASSEMBLY**

(71) Applicants: **David Lasier**, Atlanta, GA (US); **Jon VanDonkelaar**, Bellbrook, OH (US)

(72) Inventors: **David Lasier**, Atlanta, GA (US); **Jon VanDonkelaar**, Bellbrook, OH (US)

(73) Assignee: **ENERSPHERE
COMMUNICATIONS LLC**, Atlanta, GA (US)

(**) Term: **14 Years**

(21) Appl. No.: **29/498,457**

(22) Filed: **Aug. 4, 2014**

(51) LOC (10) Cl. **14-03**

(52) U.S. Cl.

USPC **D14/230**

(57) **CLAIM**

The ornamental design for communications pole with antenna-luminary assembly, as shown and described.

DESCRIPTION

FIG. 1 is a perspective view of the design in one environment;

FIG. 2 is a detail view of the portion indicated in FIG. 1;

FIG. 3 is a front view thereof;

FIG. 4 is a back view thereof;

FIG. 5 is a side view thereof;

FIG. 6 is a second side view thereof;

FIG. 7 is a top view thereof;

FIG. 8 is a bottom view thereof;

FIG. 9 is a perspective view of the design in another environment;

FIG. 10 is a front view thereof;

FIG. 11 is a back view thereof;

FIG. 12 is a side view thereof;

FIG. 13 is a second side view thereof;

FIG. 14 is a top view thereof; and,

FIG. 15 is a bottom view thereof.

The dashed lines are for illustrative purposes only and form no part of the claimed design. The dot-dash lines in the figures represent a boundary of the claim and form no part of the claimed design.

1 Claim, 7 Drawing Sheets
